TRAINER AIRCRAFT FOR SIMULATING VARIOUS GRAVITY CONDITIONS

James E. Webb, Administrator of the National Aero-
nautics and Space Administration with respect to an
invention of John C. Trotter

Filed Apr. 2, 1965, Ser. No. 84,592

Term of patent 14 years

(Cl. D71—1)

FIGURE 2

Fig. 7-3

FIG. 1 is a top plan view of a trainer aircraft for simulating various gravity conditions, showing my new design;

FIG. 2 is a side elevation thereof;

FIG. 3 is a side elevation as viewed from the right of FIG. 2; and

FIG. 4 is a side elevation as viewed from the left of FIG. 2.

I claim:

The ornamental design for a trainer aircraft for simulating various gravity conditions, substantially as shown.
